UNITED STATES PATENT OFFICE.

FRANK KONIECZKA, OF CHICAGO, ILLINOIS.

BORING-BIT.

1,169,406.

Specification of Letters Patent. Patented Jan. 25, 1916.

Application filed May 14, 1914. Serial No. 838,505.

To all whom it may concern:

Be it known that I, FRANK KONIECZKA, a citizen of the United States, residing at Chicago, in the county of Cook and State of Illinois, have invented new and useful Improvements in Boring-Bits, of which the following is a full, clear, concise, and exact description, reference being had to the accompanying drawing, forming a part of this specification.

10 My invention relates to improvements in wood boring tools.

Heretofore it has been found difficult and at times impossible to bore holes of any considerable size, especially when working in hard wood, with the ordinary form of portable hand tool. For example, plumbers, electricians, and the like who are frequently called upon to cut fairly large holes in hard 20 oak floors experience much difficulty and annoyance in the operation. Sometimes the hole will be cut by boring a circle of small holes. Tools have been devised with a view to boring large holes, but it has been found 25 that it is oftentimes impossible to obtain the proper amount of leverage without complicated rigging and there is great liability of breakage.

It is one of the objects of my invention to 30 provide a portable, manually operated bit capable of cutting holes of considerable size and one that will operate equally well in soft wood or hard.

Further objects of my invention are to 35 provide such a bit that may be used with the ordinary form of hand brace; to provide a bit of the sort described that is adjustable for boring holes of different diameters; to provide such a bit that takes the strain in 40 such a way as to avoid the danger of breakage; to provide improved forms of cutters cooperating in attaining the desired ends; and to provide a bit of the character described that is economical to manufacture, 45 easily carried about and readily operated.

Additional objects and advantages of my invention will be apparent from the following description taken in connection with the appended claim.

50 I have described in the following specification and illustrated in the accompanying drawing, one embodiment of my invention, as an example, it being clearly understood

that changes may be made in the form, construction and arrangement of the parts 55 without departing from the spirit of the invention or exceeding the scope of the appended claim, the form of invention herein disclosed being merely one preferred embodiment thereof.

60 In the drawing: Figure 1 is a view in front elevation of a bit constructed in accordance with my invention; Fig. 2 is a cross sectional view taken on the line 2—2 of Fig. 1, looking in the direction of the arrows; Fig. 3 is a similar view taken on the line 3—3 of Fig. 1; Fig. 4 is a cross sectional view of a portion of the shank showing a modification; and Fig. 5 is a cross sectional view (enlarged) taken on the line 70 5—5 of Fig. 4.

65 Like reference characters refer to like parts throughout the following description and the several figures of the accompanying drawing.

75 Referring to the drawing, the bit has a shank 10 provided with the usual squared end 11 whereby it may be stocked in the socket of an ordinary brace. The shank 10 has an internal bore which is screw-threaded 80 to engage a screw-threaded stem 12, extending up into the bore and serving as a feeding member, as hereinafter described. This stem 12 is provided, at its lower end, with a tapered portion 13, having cutting threads 85 14 formed thereon, which are broken by a pair of spiral channels 15, and a boring point 16, the whole forming, in effect, a twist drill and also forming an anchorage means along which the boring mechanism, 90 to be described later, may be fed.

95 The lower end of the shank 10 is enlarged to form a mandrel which is provided with diametrically opposed recesses 17 for the reception of the lateral arms 18 of two side cutters which seat in the recesses 17, being embraced at their top edges by downwardly projecting flanges 19 on the mandrel, and resting at the bottom on the shoulders 20 of the recesses.

100 The cutters are secured to the mandrel by means of the following plates 21 which are fastened to the mandrel by machine screws 22 and have shoulders 23 bearing against the arms 18 of the cutters and resting on 105 ledges 24 formed at the edges of the shoul-

ders 20 of the recesses the screws 22 being adjustable to securely clamp the arms 18 in place.

Substantially at right angles to the arms 18 of the cutters are downwardly extending legs 25 which are curved slightly forward and terminate in cutting edges 26 of the gouging type. At the rear thereof and extending below the same are thin cutting spurs 27, the spur of one cutter being at the outer side of the cutter, that of the other being at the inner side of its cutter. Otherwise the cutters are identical.

On the shank 10 of the bit is an aperture 15 for the passage of a catch 28, adapted when pressed inwardly to engage a slot 29 formed in the screw-threaded stem 12.

In operation the stem 12 is manually rotated until the point of the twist drill at its 20 end is considerably below the side cutters. The bit is then stocked in the socket of a brace and the catch 28 is pressed in and held as the brace is operated. It will be apparent that the engagement of the catch in the 25 slot 29 will lock the parts so that the whole device will rotate as a unit, the twist drill meanwhile boring into the wood, the chips and shavings being removed through the spiral channels 15. When the drill or boring 30 member penetrates far enough to firmly grip the wood the catch 28 is released, thus unlocking the shank 10 from the stem 12. On continued operation of the brace the shank, carrying the side cutter, will rotate 35 about the screw-threaded stem which is held stationary by its position in the wood and will feed down on the same, thus bringing the side cutters into engagement with the wood, the spurs 27 first making contact as 40 will be obvious. As these spurs are at different distances from the center, the incisions cut thereby will have the form of two concentric circles, the distance between being substantially the width of the forward 45 cutting edges 26, which, as the bit further feeds, will chisel out this portion. This action continues until the material worked upon is penetrated. It will be apparent that the wood is not cut to the full extent of the 50 hole desired, but rather a disk is cut out and accordingly there is a great economy of labor. Owing to the firm gripping purchase 55 provided by the central boring member and to the form of the side cutters, the hole can be bored quickly and easily.

In case the wood to be bored is of any considerable thickness, the above operation is carried out as far as feasible. The bit is then withdrawn leaving a circular wedge 60 which can be knocked out, whereupon the operation is repeated as often as necessary until the entire piece is penetrated.

It will be seen that holes of different diameters may be bored by altering the positions of the side cutters. By loosening the

screws 22 the arms 18 of the cutters may be shifted laterally to increase or decrease the cutting radius. The arms may be any length within the range of practicability, or a set of side cutters having arms of different lengths may be used if desired. 70

In the modification shown in Figs. 4 and 5 the internal bore of the shank 10 is smooth, and in apertures 30 in the shank are pivoted screw-threaded plates 31 adapted to engage 75 the screw-threaded stem 12 when pressed inwardly. This latter is accomplished by a cam ring 32, rotatable on the shank 10 and having cam surfaces 33 adapted to engage outwardly projecting arms 34 of the plates 80 31. It will be seen that when the ring 32 is rotated to bring the cam surfaces 33 in contact with the arms 34, the plates 31 will be held in engagement with the screw-threaded stem 12. Then when the bit is rotated the 85 shank will feed down on the stem as above described, the only difference being that the latter is in engagement merely with the plates 31 instead of with the entire inner surface of the shank. The advantage of this 90 form is that when it is desired to move the stem 12 relatively to the shank, as for example, to place the boring and gripping member in the proper position for commencing operation, instead of having to unscrew it it is only necessary to turn the cam ring 32 to allow the plates 31 to move out of engagement with the stem 12, whereupon the latter may be freely moved up and down 95 as desired. 100

Owing to the form of the rotating cutters the strain thereon is greatly lessened. The thin cutting spurs make their incisions with little strain and they leave only a narrow, thin strip to be chiseled out by the transverse cutters. Thus it will be apparent that the strain on the cutters is much less than it would be on the ordinary cutter. 105

Practically none of the strain is on the securing plates 21, as the force against the 110 side cutters binds the arms against the shoulders 19 and thus the strain is taken by the mandrel in such a manner that the liability of any of the parts breaking is to a large extent removed. 115

Thus, I have provided, by my invention, a portable, manually operated bit capable of easily and quickly boring holes of considerable size in soft or hard wood, and at the same time, a bit adjustable to bore holes of 120 various diameters.

Having thus described my invention what I claim as new and desire to secure by Letters Patent is:—

In a boring bit, a shank, a threaded stem 125 on which said shank feeds, an arm associated with said shank, a cutter carried by said arm revolving about said stem at a substantial distance therefrom, and a boring and anchoring member associated with 130

said stem having a plurality of cutting edges at the end thereof for cutting and loosening material in advance of said member, said 5 boring and anchoring member being provided with screw cutting threads for feeding it downwardly and preventing its withdrawal, and a plurality of channels leading from said cutting edges and extending across said threads affording passages for

the material cut and loosened by said cutting edges.

In witness whereof, I have hereunto subscribed my name in the presence of two witnesses.

FRANK KONIECZKA.
